UNITED STATES PATENT OFFICE

115,291

DESIGN FOR AN X-RAY UNIT

Thomas M. McDonald, Canton, Ohio, assignor to
The Weber Dental Manufacturing Company,
Canton, Ohio, a corporation of Ohio

Application October 27, 1938, Serial No. 80,699

Term of patent 7 years

To all whom it may concern:

Be it known that I, Thomas M. McDonald, a citizen of the United States, residing at Canton, in the county of Stark and State of Ohio, have invented a new, original, and ornamental Design for an X-Ray Unit, of which the following is a specification, reference being had to the accompanying drawings forming part thereof.

Figure 1 is a front perspective view of an X-ray unit, showing my new design; and

Fig. 2, a side elevation thereof, with certain of the parts of the X-ray unit in different positions of adjustment than shown in Fig. 1.

The essential features of my design reside in the parts shown in full lines.

I claim:

The ornamental design for an X-ray unit, as shown and described.

THOMAS M. McDONALD.
